UNITED STATES PATENT OFFICE.

ROBERT ECCLES, OF BALLYWALTER, IRELAND.

GEARING FOR CYCLES.

SPECIFICATION forming part of Letters Patent No. 680,235, dated August 13, 1901.

Application filed October 4, 1900. Serial No. 31,962. (No model.)

To all whom it may concern:

Be it known that I, ROBERT ECCLES, carpenter, a subject of the Queen of Great Britain, and a resident of Main street, Ballywal- 5 ter, county of Down, Ireland, have invented certain new and useful Improvements in Gear- ing for Cycles, of which the following is a specification.

This invention relates to an improved construction of tread-lever gear for cycles which is efficient in action and strong in construction.

The strain due to the working of the long tread-levers is very great, and therefore it is 15 essential that the cycle be so constructed that the parts while not being too heavy should be able to bear the strain without warping or bending in any way, and, further, that the working parts should be so made as to give 20 the minimum of friction. As will be readily understood, unless these essentials are characteristic of the gear the bicycle will not be a success. It is for want of these essential 25 characteristics that gears of a similar nature which have heretofore been made have all failed.

The object of my invention is to provide a tread-lever gear which while being strongly and simply constructed shall give the minimum of friction when working. The gear for both driving-cranks is of course the same.

In order that my said invention may be properly understood, I have hereunto appended an explanatory sheet of drawings, 35 whereon—

Figure 1 shows a bicycle fitted with the improved gear in side elevation. Fig. 2 is an enlarged side view of the gear. Fig. 3 is an enlarged front view of the gear. Fig. 4 is an 40 enlarged section through one of the joints *h*. Fig. 5 is an enlarged section through one of the fulcrum-joints *l*.

In constructing the bicycle I make the "diamond" frame *a* longer than usual and 45 with the seat-pillar tube *a'* vertical or nearly vertical.

b is the front wheel, and *c* the back wheel.

d is the chain, and *e* the chain-wheel.

f is the crank-axle.

50 The driving-cranks *g g'*, which may be

otherwise of the ordinary construction, are made somewhat shorter than usual and have jointed to them, by means of pin-and-ball joints *h*, links *i i*, which are jointed by means of pins *j* to the forked ends *k k'* of tread-levers 55 *k k*. These tread-levers are fulcrumed on pins *l*, secured in the bent arms *m m* of the forked bracket *n*, which latter is secured rigidly, by means of studs *o o* or in other suitable manner, to the seat-pillar tube *a'* of the 60 cycle-frame. Attached to the ends of the tread-levers are ordinary cycle-pedals *p p*, or, if desired, foot plates or treadles may be used instead of pedals.

As will be seen from Fig. 4, the joint *h* is 65 formed by a pin *q*, secured rigidly to the end of the crank *g*. This pin has cones *r r* upon it, and cups *s s* are inserted in the hollow *t* of the link *i*. A double set of balls *u* run between the cups and cones. In the case of the 70 fulcrum-joint (shown at Fig. 5) the pin *l* is secured rigidly in the arm *m* of the bracket *n* and has cones *v* on it. Cups *w* are inserted in the hollow of the lever *k*, and balls *x* run between the cups and cones. 75

By having the levers *k k* fulcrumed at *l* to a bracket *n*, which is secured to the tube *a'*, the whole strain of the gear when working is thrown onto the tube *a'* and the bottom bracket carrying the axle *f*, which is the 80 strongest part of the frame. Further, the fork *n* enables the strain due to the working of the two levers *k k* to be thrown equally on each side of the frame and not to any appreciable extent more to one side than the other, 85 which is a most important point. The whole strain of the levers when the driver is pedaling is thrown onto the fulcrums *l*, and by them transmitted to the arms *m*, and by them again to the tube, which being nearly vertical tends as a consequence to exert all the pressure downward onto the bottom bracket, which, as before stated, is the strongest part 90 of the machine. For the purpose of reducing friction when working, the joints and fulcrums are made with the ball-bearings. 95

With this construction of tread-lever gear great power can be transmitted to the crank-axle and chain-wheel. In practice it is found that with this gear a greater speed can be ob- 100

tained than with the ordinary gears and with no appreciably greater expenditure of muscular energy.

A cycle with this gear is found to be exceptionally suitable for ladies.

The forked bracket *n*, with the depending arms *m*, constitutes a most convenient and rigid form of support for the levers *k*.

The pivot-pins *j* at the ends of the levers may be made to work in ball-bearings.

Having now fully described my invention, what I claim, and desire to secure by Letters Patent, is—

In a cycle-gear, the combination with the driving-axle mounted on the lower end of the seat-pillar tube, of cranks *g g'* upon said axle,

links *i i'* connected to the cranks by joints *h*, tread-levers *k* fulcrumed as at *l* on fixed ball-bearing fulcrums and having their arms, *k'*, connected to the links *i i'* by joints *j*, pedals *p* upon the levers, and the forked bracket *n* secured to the seat-pillar tube and having rigid arms *m m* supporting the fixed ball-bearing fulcrums of the levers at the lower extremities of said arms, all arranged substantially as shown and described.

Signed at Belfast, county of Antrim, Ireland, this 21st day of September, 1900.

ROBERT ECCLES.
